HEATING DEVICE

Hugh Charles Hebard, Greenford, England, assignor to Aladdin Industries Limited, Greenford, England, a corporation of Great Britain

Application April 24, 1947, Serial No. 743,499
In Great Britain May 13, 1946

13 Claims. (Cl. 219—34)

1

This invention relates to electrical heating devices and radiators and has for its object to provide improved forms thereof wherein one concentrated heat source at high temperature can be utilised to heat a larger area uniformly at a lower temperature.

According to the invention an electrical heating device comprises a heating element capable of being heated to a high temperature arranged between two or more components of high conductivity and of greater area than the heating element and sheets of heat insulating material disposed closely adjacent each of said conductive components each insulating sheet being of smaller area than the adjacent conductive component.

According to one form of the invention an electric radiator comprises a number of metal sheets of different areas assembled in close parallel relationship, sheets of heat insulating material disposed between adjacent metal sheets, each insulating sheet being of smaller area than the adjacent metal sheet, and an electrical heating element disposed between two metal sheets of the assembly.

Reference will now be made to the accompanying drawings which show examples of constructions according to the invention and in which:

Fig. 1 is an elevation of an electric radiator,

Fig. 2 is a cross-sectional elevation taken on line A—B of Fig. 1,

Fig. 3 is a perspective view of the radiator shown in Figs. 1 and 2,

Fig. 4 is a sectional elevation of a modified form of radiator, and

Fig. 5 is a sectional view of a plate for use in an electric oven construction.

Referring first to Figures 1—3, the radiator illustrated comprises two plates 1 and 2 of slightly curved form constructed of light sheet metal of high thermal conductivity such as aluminium, secured to base members or feet 3, side members 4 and a front casing 5, also of sheet metal. The upper edge of the casing 5 is connected by struts 6 with the upper part of the back plate 2 whose side edges are formed with rearwardly extending flanges 7.

The electrical heating element 8 is disposed substantially centrally of and between the back plates 1 and 2 and at the rear of the plate 1 is an asbestos sheet 9 coinciding in position and area with the heating element, the asbestos sheet being backed by a plate 10 of metal such as iron. To accommodate these plates the rear plate 1 is formed or provided with a casing 11. The posi-

2

tion of the heating element 8 is shown by broken lines in Fig. 1 which also indicates its relatively small area as compared with the area of the back plates. It is capable of sustaining a temperature up to as much as 900° centigrade. At the back of plate 1 is an asbestos sheet 12. Disposed in front of the back plates is a metal plate 13 which is of substantially smaller area than the back plates which are separated from the plate 13 by an asbestos sheet 14 which is of slightly less area than the plate 13. In front of the plate 13 is another metal sheet 15 of still smaller area which is separated from the plate 13 by a sheet 16 of asbestos.

15 In the operation of the arrangement above described, the heating element 8 causes the metal plates 1 and 2 to become hot. The radiation of heat from plate 1 is reduced by the heat insulating material 12 and from plate 2 by the heat insulating material 14. The border portion of plate 2 which surrounds the edges of insulating sheet 14 thereby becomes hotter than it would do were the insulating sheet not present and consequently radiates more heat to the surrounding atmosphere. The metal plate 13 is heated by gradual conduction of heat from plate 2 through the insulating material 14. Owing to the position of the insulating sheet 16, the plate 13 is caused to radiate more heat from its portions surrounding the sheet 16 and the central metal plate 15 is heated by slow conduction of heat through the insulating sheet 16. By these means the concentrated heat source constituted by the element 8 whose temperature may reach as high as 900° centigrade is made to produce a substantially uniform, although lower temperature, over the whole front surface of the heater.

Figure 4 shows another form of radiator similar to that illustrated in Figures 1—3, but in which the heat radiation takes place equally from both sides. The heating element 17 in this construction is disposed between two parallel metal sheets 18, on the outer surfaces of which are disposed insulating sheets 19 of smaller area than the sheets 18. On the outer sides of the insulating sheets are further metal sheets 20, which in turn carry on their outer surfaces insulating sheets 21, covered by metal sheets 22. The radiator is maintained with the metal and asbestos sheets in a vertical position by supporting the larger metal sheets 18 from a base 23. In both forms of the invention shown in Figures 1—3 and 4, the radiator is not limited to the exact number of metal sheets illustrated; as this can be varied to suit conditions.

The invention can also be applied to various purposes such as the heating of cooking vessels or for industrial heating, and Fig. 5 shows one method of applying the invention to the construction of an electric oven. In this construction a heating element 24 is disposed within a heat insulating plate 25 and between two metal plates 26 and 27. The plate 26 is recessed to fit into a recess 28 in the insulating plate and the plate 27 is recessed to accommodate an insulating sheet 29 designed to reduce radiation from the centre of the metal sheet 27. The inside wall of the oven may conveniently be formed by a continuous metal sheet 30 having good contact with metal sheets 26 and 27 whereby the sheet 30 is substantially uniformly heated over its entire surface.

The unit illustrated in Fig. 5 is designed to serve either as a base or as a side component for an electric oven. This form of construction is particularly advantageous because it provides even heating throughout an oven and greatly facilitates cleaning of the interior of the oven.

Having now particularly described and ascertained the nature of my said invention and in what manner the same is to be performed, I declare that what I claim is:

1. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, and a flat high-temperature electrical heating unit back of and having a vertical heating surface closely adjacent the rear-most and largest one of said metal sheets.

2. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, and a flat high-temperature electrical heating unit back of and having a vertical heating surface closely adjacent the rear-most and largest one of said metal sheets, said heating unit having a vertical heating surface area substantially less than the front and smallest one of said metal sheets.

3. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of ma-

terial having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, and a flat high-temperature electrical heating unit back of and having a vertical heating surface closely adjacent the rear-most and largest one of said metal sheets, said sheets and said heating unit having substantially the same form and being substantially centered relatively to each other.

4. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, and a flat high-temperature electrical heating unit back of and having a vertical heating surface closely adjacent the rear-most and largest one of said metal sheets, said heating unit having a vertical heating surface area substantially less than the front and smallest one of said metal sheets, said sheets and said heating unit having substantially the same form and being substantially centered relatively to each other.

5. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, and a flat high-temperature electrical heating unit back of and having a vertical heating surface closely adjacent the rear-most and largest one of said metal sheets, said sheets and said heating unit having rectangular forms and being substantially centered relatively to each other.

6. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly

less than the area of said metal sheet next in front of it, and a flat high-temperature electrical heating unit back of and having a vertical heating surface closely adjacent the rear-most and largest one of said metal sheets, said sheets and said heating unit having rectangular forms and being substantially centered relatively to each other, said heating unit having a vertical heating surface area substantially less than the front and smallest one of said metal sheets.

7. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, a flat high-temperature electrical heating unit back of and having a vertical heating surface closely adjacent the rear-most and largest one of said metal sheets, and an additional sheet of heat insulating material back of and closely adjacent the rear-most and largest one of said metal sheets and retarding radiation rearwardly from said rear-most metal sheet.

8. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, and a flat high-temperature electrical heating unit back of and having a vertical heating surface closely adjacent the rear-most and largest one of said metal sheets, the rear-most of said metal sheets comprising two similar and spaced thicknesses of sheet metal closely adjacent the front and rear heating surfaces of said heating unit and containing said heating unit between them.

9. A radiator for space heating air by radiation, including in combination a plurality of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, and a flat high-temperature electrical heating unit back of and having a vertical heating surface closely adjacent the rear-most and largest one of said metal sheets, the rear-most of said metal

sheets comprising two similar and spaced thicknesses of sheet metal closely adjacent the front and rear heating surfaces of said heating unit and containing said heating unit between them, and an additional sheet of heat insulating material back of and closely adjacent the rear-most and largest one of said metal sheets and retarding radiation rearwardly from said rear-most metal sheet.

10. A radiator for space heating air by radiation, including in combination a first set of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, a flat high-temperature electrical heating unit back of and having a vertical heating surface closely adjacent the rear-most and largest one of said metal sheets, and a second set of sheets similar to said first set of sheets and similarly related to each other, said heating unit having a second and rear vertical heating surface closely adjacent the largest and rear-most metal sheet of said second set, whereby heat is radiated to the air in opposite directions from both sides of said radiator.

11. A radiator for space heating air by radiation, including in combination a first set of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the area of said metal sheet next in front of it, a flat high-temperature electrical heating unit back of and having a vertical heating surface closely adjacent the rear-most and largest one of said metal sheets, and a second set of sheets similar to said first set of sheets and similarly related to each other, said heating unit having a second and rear vertical heating surface closely adjacent the largest and rear-most metal sheet of said second set, whereby heat is radiated to the air in opposite directions from both sides of said radiator, said sheets and said heating unit having substantially the same form and being substantially centered relatively to each other.

12. A radiator for space heating air by radiation, including in combination a first set of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the

7
next metal sheet back of it, each of said heat insulating sheets having an area slightly less than the area of said metal sheet next in front of it, a flat high-temperature electrical heating unit back of and having a vertical heating surface closely adjacent the rear-most and largest one of said metal sheets, and a second set of sheets similar to said first set of sheets and similarly related to each other, said heating unit having a second and rear vertical heating surface 10 closely adjacent the largest and rear-most metal sheet of said second set, whereby heat is radiated to the air in opposite directions from both sides of said radiator, said sheets and said heating unit having substantially the same form and being substantially centered relatively to each other, said vertical heating surfaces of said heating unit being each of substantially less area than the outer-most and smallest one of the metal sheets of the adjacent set of sheets.

13. A radiator for space heating air by radiation, including in combination a first set of respectively continuous and vertically disposed parallel sheets of material held closely adjacent each other and including alternate conductive sheets of metal having high heat conductivity and intermediate heat insulating sheets of material having low heat conductivity, said metal sheets having exposed front marginal surfaces for heat radiation, each of said metal sheets having a substantially smaller area than and leaving exposed the marginal radiating surface of the next metal sheet back of it, each of said heat insulating sheets having an area slightly less than the

5 area of said metal sheet next in front of it, a flat high-temperature electrical heating unit back of and having a vertical heating surface closely adjacent the rear-most and largest one of said metal sheets, and a second set of sheets similar to said first set of sheets and similarly related to each other, said heating unit having a second and rear vertical heating surface closely adjacent the largest and rear-most metal sheet of said second set, whereby heat is radiated to the air in opposite directions from both sides of said radiator, said sheets of each of said set of sheets having similar rectangular forms and a substantially centered relation to each other, and said heating unit having rectangular front and back heating surfaces closely adjacent and substantially centered relatively to said sets of sheets respectively.

HUGH CHARLES HEBARD.
